FINGERNAIL MOUNTING FOR WRITING INSTRUMENTS

Sam Women Sam, Chicago, Ill.

Application October 31, 1949, Serial No. 124,550

5 Claims. (Cl. 294—25)

1

My invention relates to the utilization of a fingernail as a convenient mounting for tools such as writing instruments, stencil tracing knives, plectrums for stringed instruments, styli, scribes, finger cots, other finger guards et cetera. It relates particularly to a fastener for conveniently attacking rigidly and securely a tool to a fingernail and for conveniently detaching said tool from said fingernail, said fastener thus enabling the fingernail to serve as a convenient mounting for said tool.

An object is to provide such a fastener.

Other objects and advantages become apparent as the description proceeds.

I attain these objects by devices illustrated in the accompanying drawing, in which—

Figure 1 is a view of fastener component 1 integral with a detached portion of writing instrument 2 along the plane 1—1, Figure 3.

Figure 2 is a view of fastener component 8 and a detached portion of finger-tip 6 along the plane 2—2, Figure 5.

Figure 3 is a front view of a writing instrument 2 integral with fastener component 1.

Figure 4 is a side view of the assembly of the fastener component 1 and fastener component 8 which latter is bonded to fingernail 5 by means of intermediate adhesive coating 4.

Figure 5 is a side view of fastener component 8 bonded to a fingernail 5 of finger-tip 6.

Figure 6 is a top view of fastener component 8 integral with a thin flexible glass fabric 14; Figure 8 is a right sectional view of the same, and Figure 9 is a side view of the same.

Figure 7 is a side view of a fastener component of an alternative type which permits a writing instrument 2 to be pivoted in relation to a fingernail.

Figure 10 is an axial view of pin 7 shown in Figure 4; and Figure 11 is an end view of the same.

In Figures 1, 2, 3, 4 and 5 are shown the writing instrument 2 integral with a fastener 1 having a dove-tailed groove formed between lateral elements 1 and equal transverse holes 3 for adjustably interlocking with transverse hole 9 of equal diameter in fastener component 8 having a dove-tailed tongue which fits snugly in dove-tailed groove of fastener component 1. Fastener component 8 is adapted to be conveniently and securely bonded to fingernail 5 of finger-tip 6 by means of the intermediate adhesive coating 4. Any of the holes 3 may be alined with hole 9 and the alined holes 3 and 9 may be securely pinned by pin 7. Fastener component 1 is ad-

justable up and down in relation to fastener component 8.

The fastener component 1 may be fixed to other types of tools than writing instruments 2 and the other tools mentioned above.

The portion of pin 7 which projects out of hole 9 may have an annular groove with an open washer fitted tightly in it to hold it more securely or it may have fitted in said groove a mechanical fastener disclosed in my copending application for patent Serial Number 168,691, filed June 17, 1950, now abandoned. Pin 7 fits in alined holes 3 and 9 very tightly and frictionally.

In Figures 6, 8 and 9 is shown a fastener component 8 integral with a thin flexible glass fiber fabric 14 which latter enables component 8 to be bonded to a fingernail more securely and rigidly.

In Figure 7 is shown a writing instrument 2 integral with fastener sub-component 13 having a longitudinal central channel which is engaged by extension 12 and the top portion of the complementary sub-component 10 which latter is adapted to be conveniently and securely bonded to a fingernail. A portion of said channel of sub-component 13 is deepened to accommodate extension 12. Extension 12 and the lateral elements of said channel fit frictionally and resiliently very tightly and have alined holes which are pinned by rivet 12 so that sub-components 13 and 10 are mutually hinged very tightly by frictional contact. Fastener sub-components 13 and 10 together constitute a fastener component which can engage interlockingly fastener component 8 by means of holes 11 in a manner similar to the manner in which fastener component 1 engages fastener component 8. This type of fastener component constituted by sub-components 13 and 10 can interlock with fastener component 8 and is adjustable angularly in relation to the latter as well as being adjustable up and down in relation to it.

The fastener component 8 may remain bonded to a fingernail as long as a user desires, perhaps for many months, and enables a tool like a ball point pen to be readily fastenable detachably and at a proper adjustment in relation to the fingernail. The advantages of comfort, ease and speed of writing thus instead of the conventional manner would be obvious to anybody who needs to do much continuous writing such as ledger entry clerks and envelope addressers and who experienced writing thus. One of the advantages is avoidance of pressure of a writing instrument 55 against the middle finger, which pressure often

causes a painful and nerve irritating corn or other injury at the surface of contact.

I claim:

1. A means for mounting a tool on a fingernail comprising a dovetail tongue component securely bondable to the fingernail by a suitable adhesive, a dovetail groove component securely and rigidly attached to said tool, said groove component adapted to slidably engage said tongue component whereby the tool is longitudinally adjustable with respect to the end of the fingernail, and means cooperating with said tongue and groove components to selectively maintain said tool in given position of adjustment.

2. A means for mounting a tool on a fingernail comprising a member securely bondable to the fingernail by a suitable adhesive, another member securely and rigidly attached to said tool, said second member being complementary to said first member, said second member adapted to engage 20 said first member, and a means member to interlock securely and rigidly said first and second members while said second member engages said first member.

3. Adapted for use as the principal component of a means for mounting a tool on a fingernail, a member securely bondable to the fingernail by a suitable adhesive, said member being complementary to a secondary component which is rigidly and securely attached to said tool, said member being adapted to engage said secondary component, said member and said secondary component being interlockable securely and rigidly by a means component while said member engages said secondary component.

4. Adapted for use as a secondary component of a means for mounting a tool on a fingernail,

a member securely and rigidly attached to said tool, said member being complementary to a principal component which is securely bondable to the fingernail by a suitable adhesive, said member being adapted to engage said principal component, said member and said principal component being interlockable securely and rigidly by a means component while said member engages said principal component.

5. A means for mounting a tool on a fingernail comprising a component securely bondable to the fingernail by a suitable adhesive, another component securely and rigidly attached to said tool, said latter component being complementary to said former component, said latter component being adapted to slidably engage said latter component whereby the tool is longitudinally adjustable with respect to the end of the fingernail, and means cooperating with said former and latter components to selectively maintain said tool in a given position of adjustment.

SAM WOMEN SAM.
